METAL-CLAD SWITCH

Raymond P. Mattern, Minneapolis, Minn., assignor to Minneapolis-Honeywell Regulator Company, Minneapolis, Minn., a corporation of Delaware

Application August 9, 1941, Serial No. 406,130

14 Claims. (Cl. 200—152)

The present invention is directed broadly to a switch of the type in which electrically conductive fluid, such as mercury, makes and breaks an electric circuit by bridging and unbridging a pair of electrodes. The invention is more particularly concerned with a metal clad switch; that is, a switch in which the envelope containing the mercury is made of metal.

In such switches the metal casing is made in two parts which are separated electrically by a partition of insulating material upon which the two parts of the casing are seated. The partition is provided with an opening so arranged that for certain positions of the switch the partition separates the mercury into two separate pools, at which time the circuit through the switch is broken, and for certain other positions of the switch the two pools of mercury are joined through the opening in the partition, at which time the circuit through the switch is made. These switches may be divided into two general types, one the rotating or "button" type, the other the tilting or tubular type. My invention is applicable to both types.

One of the principal problems in the design of a metal clad switch is in getting the proper seal between the two metal parts or cups which form the casing. These switches are usually pumped and then filled with hydrogen in order to suppress arcing and reduce the heat generated in making and breaking the circuit through the switch. It is therefore very important that the switch be perfectly sealed to prevent air from getting in and hydrogen from getting out. It has been found that glass is the best seal, mainly because it thoroughly wets the two metal cups when it is in its plastic form and therefore is in intimate contact with them when it hardens.

Another problem encountered in the design of a metal clad switch is the choice of a proper material for the partition. This material must be relatively hard so that it will not be destroyed or worn away by the mercury and the electrical arcs formed during the operation of the switch. It must also be an excellent electrical insulator and be of a material which will not contaminate the mercury. In addition, this material must be able to resist thermal shock. It has been found through experience and testing that a very high grade of lava makes an excellent partition as well as certain molded ceramics having substantially the same characteristics as lava.

The metal chosen for the two metal cups is

composed roughly of about 27% chromium and the rest iron. This metal has about the same thermal expansion characteristics as the glass which seals the two cups together. It has been found however that the thermal expansion characteristics of the lava or molded ceramics which have all of the other desirable characteristics differ somewhat from those of the metal and glass.

It is therefore a prime object of the present invention to design a metal clad switch in which the glass which seals the two metal cups together is spaced from the partition to allow for differences in thermal expansion characteristics.

15 A further object is to space the glass from the partition by means of a resilient washer made of some suitable material such as asbestos. Asbestos is chosen because this washer must resist the heat of fusion of the glass.

20 It has been found that the mercury does not wet the metal cups very well and therefore the electrical resistance between the mercury and the cups is fairly high. It is a further object of the invention to avoid this difficulty by welding some metal which is readily wet by mercury, to the cups to reduce the electrical resistance between the mercury and the cups. It is also an object to so locate these metals that they are submerged in the mercury before the two pools of mercury are connected through the opening in the partition. This tends to prevent the arc from striking directly to the metal cups.

25 In certain instances it is desired that the rotating type switch be made so that it will break the circuit when it is rotated slightly in either direction from its "circuit closed" position. With a single hole through the partition it requires considerable rotation in either direction to raise the hole out of the mercury to break the circuit through the switch.

30 It is an object of the present invention to overcome the above difficulty by staggering the opening through the partition so that one end of the hole can be raised out of the mercury by a slight rotation of the switch in one direction, and the other end of the hole can be raised out of the mercury by a slight rotation of the switch in the opposite direction. It is a further object to make the partition in two parts which are rotatably adjustable with respect to each other so that the angle of rotation of the switch in each direction necessary to break the circuit may be predetermined.

35 These and other objects will readily become apparent as the following specification is read in

the light of the accompanying drawing, in which:

Figure 1 is an end view illustrating the rotary or button type switch, this view being a section taken along the line 1-1 of Figure 2;

Figure 2 is a center section of the switch shown in Figure 1 and taken along the line 2-2 of Figure 1;

Figure 3 is a view similar to that shown in Figure 2, being a center section of a slightly modified type of switch showing a two part partition;

Figures 4 and 5 are detailed views of the two parts of the partition shown in Figure 3, and

Figure 6 is a longitudinal section of a tilting or tubular type switch.

Referring now to Figure 2, the two metal cups forming the casing for the switch are indicated at 11 and 12. These two cups cooperate with a partition 13 which is composed of a high grade of lava or molded ceramic having substantially the same characteristics as lava. The partition 13 is provided with a circumferential flange 14 which forms a pair of shoulders 15 and 16. A pair of notches 17 and 18 are cut in the partition 13 and are adapted to receive the projections 20 and 21 of the two cups 11 and 12, said cups 11 and 12 seating respectively on the shoulders 15 and 16.

The cup 11 is provided with an open end 23 which is of greater diameter than the cup 12 and which extends over the flange 14 of the partition 13 and also telescopes over the open end of the cup 12. An asbestos washer 25 is placed against the shoulder 16 and the open end of the cup 12 seats against this washer. In order to seal the interior of the switch from the external atmosphere a ring of glass indicated at 26 is fused and it wets the two metal cups and seals the annular space between the two cups. The glass is also sealed to the asbestos washer 25.

It will be obvious that the asbestos washer will be capable of absorbing any differential expansion which may occur between the partition 13 on the one hand, and the glass and metal cups on the other, due to variations in temperature.

The metal cup 12 is provided with an opening 27 through which the switch may be partially filled with some suitable electrically conducting fluid indicated at 28. For the purposes of this description this fluid will be referred to as mercury although any other suitable type of electrically conducting fluid may be used if desired. The air within the interior of the switch is also removed through the opening 27 and the space is filled with hydrogen gas after which a metal ball is inserted in the opening 27 and welded therein as indicated at 30.

The partition 13 is provided with an opening indicated at 31 by means of which the two pools of mercury 32 and 33 may be connected when the opening 31 is in the position shown in Figure 2. The switch is mounted for rotation by means of resilient washer type blades 34 which may also act as electrical conductors for connecting the switch in an electrical circuit. These blades 34 may be of the type disclosed in my Patent Number 2,260,754, issued October 28, 1941. An insulating handle 36 may be suitably attached in any desired manner to the circumference of the switch. The proper position for the handle may be determined by the position of the depression 20 in the cup 11, which in this instance is located opposite the opening 31 through the partition 13. It is obvious that rotation of the handle 36 will cause the switch to rotate and lift the opening 31 out of the mercury 28, at which

time the partition will divide the mercury into two separate pools and therefore break the circuit through the switch. The switch is indicated in Figure 1 with the operating handle in mid position. In order to move the switch to its "off" position and break the circuit, the handle is lowered approximately 10° below the horizontal, which action raises the opening 31 above the level of the mercury. In order to move the switch to its "on" position and close the circuit, the handle is raised to a position about 10° above the horizontal, at which time at least a portion of the opening 31 is below the level of mercury.

It has been found that the mercury does not wet the metal cups 11 and 12 satisfactorily and therefore the electrical resistance between the mercury and the cups is comparatively high, thus increasing the heat generated within the switch when the current is flowing therethrough. In order to eliminate this difficulty, a pair of contact elements indicated at 37 and 38 are welded to the metal cups. These contacts are composed of material which is readily wet by the mercury, preferably nickel, and therefore the resistance between the mercury and these contacts is relatively low. Inasmuch as the contacts are welded to the metal cups, the resistance between them is also low and therefore the overall resistance of the switch is reduced by this expedient. It has been found that the shape and position of these contacts as shown in the drawing give the most satisfactory results. It will be noted that a portion of these contacts are opposite the opening 31 and that they are so positioned that a portion of them is immersed in the mercury before the opening 31 is lowered sufficiently to permit the mercury to flow therethrough and close the circuit through the switch. This assures a good contact between each pool of mercury and its associated metal cup before the circuit is closed through the opening 31, this action tending to prevent the striking of an arc directly to one of the metal cups.

When the cups 11 and 12 are formed and the contacts 37 and 38 welded thereto the depressions 20 and 21 will have a predetermined relationship with respect to the contacts 37 and 38 so that when the switch is assembled and the depressions are located in the grooves 17 and 18, the contacts 37 and 38 will be positioned properly with respect to the opening 31. Also when the handle 36 is located on the switch adjacent the depression 20 the switch will be in the proper position to control the circuit when the handle projects through the usual wall plate.

The switch just described is used when it is desired to mount the switch in such a manner that it is always rotated in one direction to break the circuit and in the opposite direction to make the circuit. In some instances, it may be desired to have a switch which in one position makes the circuit but which will break the circuit when rotated a slight amount in either direction from its made position. If the switch shown in Figures 1 and 2 were to be used for this purpose, the opening 31 would be located in its lowermost position for the made position of the switch. It can readily be seen that a considerable rotation would be necessary in either direction in order to break the circuit through the switch. The switch shown in Figures 3, 4 and 5 has been designed with a staggered opening through the partition so that a slight rotation of the switch in either direction will cause one or the other of the two ends of the opening to be raised above the

level of the mercury and therefore break the circuit.

The switch of Figure 3 is provided with a pair of metal cups generally similar to those shown in Figure 2. They are indicated at 40 and 41. The partition in this instance is composed of two separate members 42 and 43, each having a cut-away portion forming an intermediate chamber 44. The member 42 is provided with an opening 45 and the member 43 is provided with an opening 46, these two openings being offset with respect to each other. The two parts of the partition are provided with interfitting shoulders indicated at 47 and in assembling the switch the two pieces 42 and 43 are rotated with respect to each other until the two openings 45 and 46 have the correct angular relationship with respect to each other, at which time the two pieces 42 and 43 are connected together by means of a high temperature cement located at 48. The switch is then assembled in the same manner as described in connection with the modification shown in Figures 1 and 2, being sealed by means of an annular fused glass member 49 which seats against an asbestos washer 50.

Figure 4 illustrates the member 42 and shows the position of the opening 45 with respect to the vertical. Figure 5 shows the member 43 and indicates the position of its opening 46 with respect to the vertical. Looking at these figures, it will be seen that a slight rotation of the switch in a counterclockwise direction will cause the opening 45 to be raised above the level of the mercury and break the circuit through the switch and also a slight clockwise rotation of the switch from the position indicated in Figures 4 and 5 will cause the opening 46 to be raised above the level of the mercury and break the circuit through the switch. This switch is therefore much more sensitive to rotation in either direction than would be the switch of Figures 1 and 2. Moreover, the two members 42 and 43 may be adjusted rotatably with respect to each other before the switch is assembled in order to predetermine the angular rotation of the switch in each direction necessary to break the circuit.

It will be understood that this switch may be filled with mercury and hydrogen through the opening 51 in the same manner as the switch shown in Figure 2. The opening 51 is then sealed by means of a metal ball, not shown, which is welded in the opening 51.

The switch shown in Figure 6 is of the tubular type as distinguished from the button type shown in the first five figures. This switch is provided with a partition 60 having a rather large center opening. The partition 60 is provided with a circumferential flange 61 which forms a shoulder 62. A relatively long tube 63 has an enlarged open end 64 forming a shoulder which seats against the shoulder 62 of the partition 60. A smaller metal cup 65 has an open end which telescopes within the open end 64 or tube 63 and seats against an asbestos washer 66, which in turn seats against the opposite side of the flange 61. The space between the open end 64 of the tube 63 and the cup 65 is sealed by means of fused glass, indicated at 67, which is also sealed to the asbestos washer 66 which absorbs any differential of expansion between the partition 60 on the one hand and the glass and metal members on the other.

This switch is adapted to contain a quantity of mercury which in one position of the switch will be divided into two separate pools by the parti-

tion 60, at which time the circuit through the switch will be broken. Tilting the switch in a counter-clockwise direction, as seen in Figure 6, will cause the mercury to flow towards the left-hand end of the switch and close the circuit between the two metal members through the opening in the partition 60. The rotative position of this switch about its longitudinal axis does not have any effect in so far as the control of the circuit is concerned.

In order to assure a good electrical contact between the mercury and the metal members, a pair of rings 68 and 69 are welded to the metal members 63 and 65, respectively. These rings are formed of a metal which is readily wet by the mercury, as in the modification shown in Figures 1 and 2, and therefore forms a good electrical contact therewith. These rings are so positioned that they will be contacted by the mercury at the time the two pools of mercury are joined through the partition 60.

The metal cup 65 is provided with a tubular member 70 through which the switch may be filled with mercury and hydrogen. The tubular member 70 is then sealed off and may be used as one terminal of the switch.

The partition is cut away as shown at 71 so that it will retain a larger quantity of mercury when the switch is tilted in a clockwise direction to break the circuit.

It will therefore be seen that I have designed a metal clad switch which may be efficiently sealed by means of fused glass and which may utilize a partition of any desired material without regard to the thermal expansion characteristics with respect to the glass or the metal portion of the switch. It will further be seen that I have designed a switch which is very sensitive to rotation in either direction from a made position and in which the sensitivity to rotation may be predetermined at the time the switch is assembled. Various changes and modifications of the switches disclosed may occur to those who are skilled in the art, and I therefore wish it to be understood that the specific embodiments disclosed are for the purpose of illustrating my invention and that I intend to be limited only by the scope of the appended claims.

I claim as my invention:

50. 1. A switch comprising in combination, a pair of oppositely disposed dished metal cups, a partition of insulating material interposed between said cups separating them electrically, a quantity of electrically conductive fluid partially filling said cups, said fluid being separated into two pools by said partition, an opening in said partition whereby said two pools of fluid are connected through said opening for certain positions of said switch, an annular member of glass located between said cups and sealed thereto for sealing the interior of said cups from the atmosphere, and a compressible member located between said partition and glass member to prevent said glass member from wetting said partition, whereby said partition and glass members may expand relatively to each other upon changes in temperature.

70. 2. A switch comprising in combination, a pair of oppositely disposed dished metal cups, a partition of insulating material interposed between said cups separating them electrically, a quantity of electrically conductive fluid partially filling said cups, said fluid being separated into two pools by said partition, an opening in said partition whereby said two pools of fluid are con-

nected through said opening for certain positions of said switch, an annular member of glass located between said cups and sealed thereto for sealing the interior of said cups from the atmosphere, and an asbestos member located between said partition and glass member to prevent said glass member from wetting said partition, whereby said partition and glass members may expand relatively to each other upon changes in temperature.

3. A switch comprising in combination, a pair of oppositely disposed dished metal cups, a partition of insulating material interposed between said cups separating them electrically, a quantity of electrically conductive fluid partially filling said cups, said fluid being separated into two pools by said partition, an opening in said partition whereby said two pools of fluid are connected through said opening for certain positions of said switch, said cups having relatively telescoping portions, and an annular member of glass located between the telescoping portions of said cups and sealed thereto for sealing the interior of said cups from the atmosphere, said glass member being spaced from said partition to prevent the glass member from wetting said partition, whereby said cups and partition may expand relatively to each other upon changes in temperature.

4. A switch comprising in combination, a pair of oppositely disposed dished metal cups, a partition of insulating material interposed between said cups separating them electrically, a quantity of electrically conductive fluid partially filling said cups, said fluid being separated into two pools by said partition, an opening in said partition whereby said two pools of fluid are connected through said opening for certain positions of said switch, said cups having relatively telescoping portions, an annular member of glass located between the telescoping portions of said cups and sealed thereto for sealing the interior of said cups from the atmosphere, and a compressible member separating said partition and glass members to prevent the glass member from wetting said partition, whereby said compressible member will absorb any differential expansion between said partition and glass member upon changes in temperature.

5. A switch comprising in combination, first and second metal cups, said first cup having a first portion of substantially the same diameter as said second cup and an open end portion of larger diameter, a cylindrical insulating partition having reduced portions forming opposed shoulders, said second cup fitting over one reduced portion, the first portion of said first cup fitting over said other reduced portion, said larger open end portion of said second cup extending over said partition and telescoping with respect to the open end of said second cup, a quantity of electrically conductive fluid partially filling said cups, said fluid being separated into two pools by said partition, an opening in said partition whereby said two pools of fluid are connected through said opening for certain positions of said switch, and sealing means between the open end portions of said cups for sealing the interior of said cups from the external atmosphere.

6. A switch comprising in combination, first and second metal cups, said first cup having a first portion of substantially the same diameter as said second cup and an open end portion of larger diameter, a cylindrical insulating parti-

tion having reduced portions forming opposed shoulders, said second cup fitting over one reduced portion, the first portion of said first cup fitting over said other reduced portion, said larger open end portion of said second cup extending over said partition and telescoping with respect to the open end of said second cup, a quantity of electrically conductive fluid partially filling said cups, said fluid being separated into two pools by said partition, an opening in said partition whereby said two pools of fluid are connected through said opening for certain positions of said switch, and a glass member sealed between the open end portions of said cups for sealing the interior of said cups from the external air, said glass being spaced from said partition.

7. A switch comprising in combination, first and second metal cups, said first cup having a first portion of substantially the same diameter as said second cup and an open end portion of larger diameter, a cylindrical insulating partition having reduced portions forming opposed shoulders, said second cup fitting over one reduced portion, the first portion of said first cup fitting over said other reduced portion, said larger open end portion of said second cup extending over said partition and telescoping with respect to the open end of said second cup, a quantity of electrically conductive fluid partially filling said cups, said fluid being separated into two pools by said partition, an opening in said partition whereby said two pools of fluid are connected through said opening for certain positions of said switch, a glass member sealed between the open end portions of said cups for sealing the interior of said cups from the external air, and a compressible washer between said glass member and said partition for absorbing any differential expansion between said glass and partition upon changes in temperature.

8. A switch comprising in combination, first and second metal cups, said first cup having a first portion of substantially the same diameter as said second cup and an open end portion of larger diameter, a cylindrical insulating partition having reduced portions forming opposed shoulders, said second cup fitting over one reduced portion, the first portion of said first cup fitting over said other reduced portion, said larger open end portion of said second cup extending over said partition and telescoping with respect to the open end of said second cup, a quantity of electrically conductive fluid partially filling said cups, said fluid being separated into two pools by said partition, an opening in said partition whereby said two pools of fluid are connected through said opening for certain positions of said switch, sealing means between the open end portions of said cups for sealing the interior of said cups from the external atmosphere, and a compressible washer between one of said cups and the adjacent shoulder on said partition to absorb any differential expansion between said cups and said partition on changes in temperature.

9. A switch comprising in combination, first and second metal cups, said first cup having a first portion of substantially the same diameter as said second cup and an open end portion of larger diameter, a cylindrical insulating partition having reduced portions forming opposed shoulders, said second cup fitting over one reduced portion, the first portion of said first cup fitting over said other reduced portion, said larger open end portion of said first cup extend-

ing over said partition and telescoping with respect to the open end of said second cup, a quantity of electrically conductive fluid partially filling said cups, said fluid being separated into two pools by said partition, an opening in said partition whereby said two pools of fluid are connected through said opening for certain positions of said switch, a glass member sealed between the open end portions of said cups for sealing the interior of said cups from the external air, and a compressible washer between said glass and said partition and between the open end of said second cup and the adjacent shoulder of said partition for absorbing any differential expansion between said glass and cups on the one hand and partition on the other.

10. A rotary electric switch comprising in combination, a pair of opposed metal cups, a partition in the form of a disc, said cups being seated on opposite sides of said partition and being electrically separated thereby, a quantity of electrically conductive fluid partially filling said cups and separated into two pools by said partition, means supporting said switch for rotation about the axis of said cups, an opening through said partition, said opening being alternately raised and lowered into and out of said fluid for alternately connecting and separating said two pools as said switch is rotated back and forth, means between said cups for sealing their interior from the exterior atmosphere, and a metal readily wet by said fluid in intimate electrical contact with at least one of said metal cups, one portion of said metal being opposite said opening through said partition and another portion extending toward said fluid whereby said metal is always in contact with said fluid before said opening is lowered to permit connection of said two pools of fluid.

11. A switch of the tilting type comprising in combination, a pair of opposed metal cups, a partition in the form of a disc, said cups being seated on opposite sides of said partition and being electrically separated thereby, a quantity of electrically conductive fluid partially filling said cups and separated into two pools by said partition, an axial opening through said partition, said switch being adapted to be tilted back and forth for alternately separating and connecting said pools of fluid through said opening, rings of metal of the iron group in intimate electrical contact with each cup, said rings being so located as to be immersed in said fluid before the two pools are connected through the opening in said partition and having a portion opposite said opening, and means between the cups for sealing their interior from the external atmosphere.

12. A rotary electric switch comprising in combination, a pair of oppositely disposed metal cups, a partition of insulating material between said cups separating them electrically, and a quantity of electrically conductive fluid partially filling said cups, said fluid being separated into two pools by said partition, said cups being provided with means for mounting said switch for rotation about the axis of said cups, said partition being formed by two generally similar disks which are mounted in annular engagement with each other, each disk being provided with an opening therethrough, one of said disks having a chamber formed therein for connecting said openings for closing the circuit through said switch when both of said openings are below the surface of said liquid, said chamber being of such configuration that when both of said openings in the disks are

below the level of the electrically conductive fluid a portion of said chamber extends above the level of the electrically conductive fluid, said disks being capable of assuming various different 5 rotative positions with respect to each other for varying the angle through which the switch must be rotated in each direction in order to raise the corresponding opening out of the liquid and hence break the electrical circuit through said switch.

13. A rotary electric switch comprising in combination, a pair of oppositely disposed metal cups, a partition of insulating material between said cups separating them electrically, and a quantity of electrically conductive fluid partially filling said cups, said fluid being separated into two pools by said partition, said cups being provided with means for mounting said switch for rotation about the axis of said cups, said partition being 15 formed by two generally similar disks which are mounted in annular engagement with each other, each disk being provided with an opening therethrough, each of said disks having an opposed recess thereby forming a chamber for connecting said openings for closing the circuit through said switch when both of said openings are below the surface of said liquid, said chamber being of such configuration that when both of said openings in the disks are below the level 20 of the electrically conductive fluid a portion of said chamber extends above the level of the electrically conductive fluid, said disks being capable of assuming various different rotative positions with respect to each other for varying the angle 25 through which the switch must be rotated in each direction in order to raise the corresponding opening out of the liquid and hence break the electrical circuit through said switch.

14. A rotary electric switch comprising in combination, a pair of oppositely disposed metal cups, a partition of insulating material between said cups separating them electrically, and a quantity of electrically conductive fluid partially filling said cups, said fluid being separated into 40 two pools by said partition, said cups being provided with means for mounting said switch for rotation about the axis of said cups, said partition being formed by two generally similar disks which are provided with annular interfitting portions for properly positioning said disks, one of said cups housing said two disks each disk being provided with an opening, said two disks together forming an enlarged chamber for connecting said openings for closing the circuit through said switch when both of said openings are below the surface of said liquid, said chamber being of such configuration that when both of said openings in the disks are below the level of 45 the electrically conductive fluid a portion of said chamber extends above the level of the electrically conductive fluid, said disks being capable of assuming various different rotative positions with respect to each other for varying the angle through 50 which the switch must be rotated in each direction in order to raise the corresponding opening out of the liquid and hence break the electrical circuit through said switch, an annular member of glass located between said cups and sealed thereto for sealing the interior of said cups from the atmosphere, and a resilient washer between said glass member and said partition for absorbing any differential expansion between said glass and partition upon changes in temperature.
